UNITED STATES PATENT OFFICE.

NELS L. OLSON, OF DETROIT, MICHIGAN.

HEAT-TREATING CONTAINER.

Application filed May 19, 1921. Serial No. 470,928.

To all whom it may concern:

Be it known that I, NELS L. OLSON, a citizen of the United States of America, residing at Detroit, in the county of Wayne and State of Michigan, have invented certain new and useful Improvements in Heat-Treating Containers, of which the following is a specification, reference being had thereto in the accompanying drawings.

This invention relates to the equipment used for the heat treatment of steel such as is necessary for the improvement of many steel parts produced for the automotive industries, and particularly to containers used for carbonizing operations.

The common practice is to pack the steel parts to be carbonized in a metal box with case-hardening material. Each box being opened at the top, a cover is laid on it and a seal made by means of wet fire clay inserted between the box and cover. The box or boxes are then placed in a heating furnace and brought up to the required temperature. Under such conditions, carbonic oxide gas is generated and the surface of the steel to be treated, being red hot, absorbs carbon from the gas thus producing on the steel parts a carbonized case capable of responding to ordinary hardening and tempering operations.

The seal between the box and cover must be perfect, otherwise the gas escapes from the box and no carbonizing takes place.

The fire clay seal is not satisfactory, for the reason that clay shrinks and cracks under the heat and allows some of the gas to escape. Furthermore, another difficulty encountered is that after repeated heatings and cooling-offs the box loses its original shape, warps and cracks and makes it increasingly difficult to maintain a tight joint.

The carbonizing boxes being cast, it is necessary in order to remove the pattern used in their manufacture from the sand mold, to give these boxes a tapered shape, that is, to make them a little smaller at the bottom than they are at the top. Now, when the battery of boxes are inserted in a furnace, it is desirable to place them as close as possible to one another in order to take advantage of the full capacity of the furnace and at the same time to allow enough space between the boxes for the heating gases to travel. Due to the tapered shape of the containers, when they are arranged with all the

covers on top, it is readily understood that the boxes are closer together at the top than they are at the bottom, and in order to fill the furnace to capacity it is necessary to have them come in contact with one another at the top. This has a tendency to localize the heat at the upper parts of the boxes, and this is shown in practice by the fact that the boxes oxidize or scale off at the top much faster than at the bottom; many boxes with still serviceable bottoms are scrapped because the upper parts are burnt off.

One of the objects of my invention is to provide a box or container so constructed that heat cannot alter its shape when used for heat treating purposes. Another object of my invention is to obviate the necessity of using fire clay or similar material to produce a seal between the box and lid.

A further object of my invention is to provide carbonizing boxes or containers of novel shape and by which a method of arranging the boxes and containers of a furnace may be carried into effect to insure uniform passageways between the boxes within the furnace.

A further object of my invention is to provide a heat treating box with openings whose combined area is less than the cross sectional area of the box, thus affording gussets at the corners of the box for lending rigidity to the walls thereof against warping when subjected to heat within a furnace.

The above and other objects are attained by boxes or containers of various forms, some of which are shown in the drawings wherein—

Figure 1 is a plan of an ordinary box extensively used in heat treating plants, showing by dash lines how the walls thereof warp;

Fig. 2 is a plan of a box embodying my invention;

Fig. 3 is a longitudinal sectional view of the same with lids in proximity thereto;

Fig. 4 is an end view of a box;

Fig. 5 is a plan of a small box;

Fig. 6 is a longitudinal sectional view of the same, showing the lid in proximity thereto;

Fig. 7 is a longitudinal sectional view of a modified form of box with a lid in proximity thereto;

Fig. 8 is a bottom plan view of the same;

Fig. 9 is an end view of a box.

Fig. 10 is a plan of a lid that may be used in connection with my boxes;

Fig. 11 a side elevation of the same;

5 Fig. 12 is a plan of a battery of boxes;

Fig. 13 a side elevation of the same.

In order that the purpose of my invention may be more clearly understood, I have shown in Fig. 1 an oblong box 1 and the side 10 walls 2 of this box have been warped or bulged, as indicated by dash lines, due to the extensive use in a furnace wherein the box has been subjected to heat to carbonize the contents of the box. As pointed out in the 15 beginning, such a box is closed by a lid and sealed by use of fire clay, and it is obvious that when the walls are warped, cracked or other than their original shape and condition, that it is practically impossible to fit 20 lids on such boxes and thoroughly seal the same.

To prevent warping and bulging of the box or container walls, I make a box 3 with a top wall 4 provided with one or more circular lid openings 5 and that part of the wall 4, which is not cut away, provides gussets and webs which re-inforce and stiffen the walls of the box or container, particularly at the corners of the box. The box 30 which has two openings, as shown in Fig. 2, has a central web portion which constitutes a tie or brace between the sides walls of a box.

The bottom of the box 3 has a plurality 35 of legs 6 and said box is adapted to have its openings 5 closed by lids 7, said lids having the peripheral edges thereof beveled or tapered and adapted to snugly wedge or fit in the openings 5. The walls of the openings 40 5 can be machined to insure a perfect lid fit and should the lids stick or bind within the openings 5, tapping on the lid will tend to loosen the same. To facilitate removal of the lids, I may provide the same with lugs 8 45 projecting outwardly from said lids and overhanging the top wall 4 of the box or container, and if the lids can not be removed by tapping the lugs with a hammer, a crow-bar can be inserted between the top wall 4 50 and said lugs and the cover pried off without difficulty.

In Figs. 7, 8, and 9, I show a box 9 having an end opening 10 adapted to be closed by a lid 11 and this box has been especially 55 designed for carbonizing long parts, as cam and crank shafts, which may be placed in the box when on end. This box also has feet 12 to maintain the box in spaced relation to the bottom of a furnace.

60 Considering the battery of boxes shown in Figs. 12 and 13, each box has side walls 13 tapering inwardly from the top of the box to the bottom thereof and the bottom of the box has legs 14, while the top thereof has 65 a circular opening 15 adapted to be closed by

a lid 16, somewhat similar to the lid shown in Figs. 10 and 11. The lugs on the lid 16 will serve as feet, when the box is inverted and it will be noted that alternate boxes can be placed in such inverted positions so that there will be uniform passages 17 between 70 the boxes and under the bottoms thereof. Such spaces will even exist if the boxes are placed in superposed relation and by leaving a uniform space about all of the boxes there 75 can be a thorough circulation of the heating gases, which insures a uniform heat and prevents one part of a box being heated to a greater extent than another. The arrangement of the boxes also contributes to a full 80 capacity furnace, and by reversing the position of the boxes, from one heat to another, there will be a uniform wear and greater length of service for the boxes.

It is obvious that when a box is inverted 85 that the weight of the same insures a seal sufficient to retain carbonizing gases within the box, and I attach considerable importance to the configuration of the boxes which permits of compact arrangement of the same 90 within a furnace.

What I claim is:—

1. Heat treating containers for carbonizing parts sealed in said containers and wherein the containers are subjected to heat 95 within a furnace, said containers having side walls tapered inwardly from the upper ends of said containers to the lower ends thereof which permits of inverted containers co-operating with upright containers in providing uniform passages between side walls of adjacent containers when arranged in laterally extending rows.

2. Heat treating containers for carbonizing parts sealed in said containers and 100 wherein the containers are subjected to heat within a furnace, said containers having a configuration which permits of inverted containers cooperating with upright containers in providing uniform passages about adjacent 110 containers, and lids for the containers having lugs serving as feet for the inverted containers.

3. As a new article of manufacture, a heat treating container tapered from top to 115 bottom, legs on the bottom of the container, and a lid for the top of the container, said lid having lugs serving as feet when the container is inverted.

4. As a new article of manufacture, a substantially rectangular heat treating container having an opening affording gussets at the side walls of said container, and a lid closing and sealing said container by frictionally engaging walls of the container 125 opening.

5. As a new article of manufacture, a heat treating container, a lid therefor, and means carried by said lid serving as supports for said container when inverted and 130

facilitating removal of said lid when the container is upright.

6. A method of arranging heat treating containers in a furnace, consisting in utilizing individual unitary containers of like configuration and placing the containers in lateral rows in proximity to one another to form passages of uniform width below and around said containers.

10 7. A method of sealing a lid relative to

a heat treating container, consisting in snugly fitting the lid in the container, and then inverting the container so that the weight thereof is borne by the lid.

In testimony whereof I affix my signature 15 in presence of two witnesses.
